Wis., assignors to Acme Die Casting Corp., Racine,
Wis.

Filed Oct. 12, 1959, Ser. No. 57,903

Term of patent 14 years

(Cl. D77—1)

Fig. 1 is a side perspective view of cranking starter for a gasoline engine showing our new design.

Fig. 2 is a fragmentary side perspective view thereof, showing the handle in its folded position.

Fig. 3 is a longitudinal sectional view of the handle in the open position as in Fig. 1.

The side not shown is substantially like the side shown.

We claim:

The ornamental design for a cranking starter for a gasoline engine, substantially as shown and described.
